UNITED STATES PATENT OFFICE.

CONSTANTINE WAGNER, OF NEW YORK, N. Y.

DESIGN FOR A BOTTLE.

SPECIFICATION forming part of Design No. 28,532, dated May 3, 1898.

Application filed January 28, 1898. Serial No. 888,354. Term of patent 7 years.

To all whom it may concern:

Be it known that I, CONSTANTINE WAGNER, of New York city, in the county and State of New York, have invented and produced a new and original Design for a Bottle, of which the following is a full, clear, and exact specification.

Reference is to be had to the accompanying drawings, forming a part of this specification, in which similar characters of reference indicate corresponding parts in all the figures.

Figure 1 is a perspective view of a bottle, showing the design. Fig. 2 is a sectional side elevation of the same, and Fig. 3 is a sectional plan view of the same.

The leading feature of my design consists of a two-bore single neck A, rising from the

apex of the tapering top B' of the bottle-body B, a portion A' of the neck A appearing as depending from the top B' within the body B, 20 to the exterior surface of the neck presenting an unbroken continuity in a transverse direction.

Minor features of the design consist of the flaring mouth A² on one side of the neck near 25 the top thereof and in the angular terminal A³ at one side of the said mouth.

I claim—

The design for a bottle, as herein shown and described.

CONSTANTINE WAGNER.
